UNITED STATES PATENT OFFICE.

MARGARET KELLEY, OF LOS ANGELES, CALIFORNIA, ASSIGNOR, BY MESNE ASSIGNMENTS, TO AUTOMATIC FLATWORK FOLDER COMPANY, A CORPORATION OF ARIZONA.

MACHINE FOR FOLDING FABRIC ARTICLES.

1,376,942.

Specification of Letters Patent.

Patented May 3, 1921.

Application filed November 21, 1919. Serial No. 339,653.

To all whom it may concern:

Be it known that I, MARGARET KELLEY, a citizen of the United States, residing at Los Angeles, in the county of Los Angeles and 5 State of California, have invented new and useful Improvements in Machines for Folding Fabric Articles, of which the following is a specification.

This invention relates to a mechanism 10 which is especially adapted to be employed as an attachment to mangles in laundry operations for the purpose of folding sheets, table cloths, counterpanes, and similar articles on discharge of same from the mangle. 15 It is the object of this invention to provide a machine of the above character, embodying a means whereby sheet material may be laid in successive folds, and embodying an effective feeding mechanism capable 20 of operating on fabrics of various characters without danger of mutilation or damage to the material.

Another object is to provide a folding machine whereby the sheet fabric may be 25 folded in successive layers and afterward refolded lengthwise of such layers.

Another object is to provide a driving mechanism for a folding machine of the 30 above type, which is adapted to be driven from the driving mechanism of a mangle and to be timed relative to the latter so as to properly fold the articles delivered successively from the mangle.

Other objects will appear hereinafter. 35 The invention is illustrated in the accompanying drawings in which:

Figure 1 is a view of the folding machine as seen in front elevation with portions of the frame thereof removed;

Fig. 2 is an enlarged detail section and elevation as seen on the line 2—2 of Fig. 1;

Fig. 3 is a detail in end elevation as seen in the direction indicated by the arrow 3 in Fig. 1, frame portions being removed;

Fig. 4 is a view in end elevation as seen in the direction indicated by the arrow 4 in Fig. 1 with parts of the frame broken away;

Fig. 5 is an enlarged detail horizontal 50 section as seen on the line 5—5 of Fig. 4;

Fig. 6 is a view in section and elevation as seen on the line 6—6 of Fig. 4;

Fig. 7 is a view in elevation as seen in the direction indicated by the arrow 7 in Fig. 4 showing the driving parts of the final

folding mechanism with the feed belt portions removed.

The invention primarily resides in providing a pair of endless feed belts arranged substantially parallel to each other with the 60 adjacent belt portions disposed close together and driven in corresponding directions and between which the sheet fabric to be folded may be fed; these belts being mounted for oscillatory movement whereby 65 the sheet fabric, on being discharged from between the belts, will be laid in successive folds.

A pair of such folding devices are employed, one for initial folding of the article 70 on its discharge from the mangle and particularly indicated at *a* in Fig. 3, and the other employed for finally folding the previously folded article and indicated at *b* in Figs. 1 and 6.

In the initial folding device *a*, 8 and 9 indicate the endless feed belts which are arranged substantially parallel with each other and mounted to travel in approximately a vertical direction. The belt 8 80 passes around horizontally extending rollers 10 and 11, rigidly mounted on shafts 12 and 13; the shaft 12 being supported in suitable bearings 14 carried on a stationary frame of any suitable construction. The shaft 13 85 is carried on the lower ends of dependent rocker arms 15 pivoted to swing on the shaft 12.

The belt 9 is mounted on rollers 16 and 17 90 extending parallel with the rollers 10 and 11; the roller 16 being mounted on a shaft 18 carried on brackets 19 extending forwardly from the upper portion of the rocker arms 15, and the roller 17 being mounted on a shaft 20 carried on the lower ends of 95 the rocker arms. The rollers 11, 16 and 17 are thus carried on the rocker arms and are movable therewith axially of the roller 10.

Slack adjusting rollers 21 and 22 are carried on adjustable bearings mounted on 100 brackets 23 affixed to the rocker arms 15; the rollers 21 and 22 bearing against the inner sides of the outer portions of the belts, as particularly shown in Fig. 3.

The rocker arms 15 are designed to be 105 oscillated so that the lower portions of the belts 8 and 9 will be swung back and forth on an arc. For this purpose a pair of cranks 24 are provided and are pivoted relative to the shaft 12 adjacent to the outer sides of 110

the bearings 14 and having downwardly extending portions 25 connecting with the rocker arms; the cranks having their outer ends attached to connecting rods 26 which 5 extend downwardly and have their lower ends mounted on wrist pins 27 carried on rotary elements, here shown as comprising spur gears 28 mounted on stud shafts 29 and adapted to be rotated by pinions 30 mounted on a shaft 31.

10 The shaft 31 is designed to be driven in synchronism with a mangle and for which purpose is fitted with a sprocket wheel 32 engaged by a sprocket chain 33 adapted to be driven by any suitable rotary member on the mangle.

15 The shaft 12 and the roller 10 are driven from the shaft 31 by a sprocket chain 34 passing around a sprocket wheel 35 on the shaft 31 and a sprocket wheel 36 on the shaft 12. The roller 11 and shaft 13 are driven from the shaft 12 by a sprocket chain 37 passing around a sprocket wheel 38 on the shaft 13 and a sprocket wheel 39 on the 20 shaft 12. The sprocket chains 34 and 37 are here shown as arranged on the right hand end of the machine, as shown in Figs. 1 and 3.

25 Mounted on the end of the shaft 13 at the left hand end of the machine, as shown in Figs. 1 and 2, is a pinion 40 which meshes with an idler pinion 41 on a stud shaft 42 carried by the rocker arm 15, the pinions 40 and 41 constituting a reverse gear. A sprocket wheel 43 is mounted on the idler pinion 41 around which passes a sprocket chain 44 leading around a sprocket wheel 45 on the shaft 18, by which the latter is rotated in a direction opposite that of the shaft 12. 30 Arranged adjacent the sprocket wheel 45 on the shaft 18 is a sprocket wheel 46 around which passes a sprocket chain 47 leading around a sprocket wheel 48 on the shaft 20, by which the latter and the roller 17 are rotated from the shaft 18.

35 The articles to be delivered from the mangle between the belts 8 and 9 may be fed directly from the roller 49 of the mangle to the roller 10, but I have here shown an intermediate feeding belt 50 which passes around a roller 51 on the shaft 31 and a roller 52 mounted on the shaft 53 carried by the bearing 14; the roller 51 being positioned beneath the mangle roller 49 and the 40 roller 52 disposed adjacent to the feed roller 10 and sufficiently there above that the sheet article passing from the mangle roller 49 onto the belt 50 will be discharged over the roller 52 onto the belt 8 passing over the roller 10. The roller 51 is driven with the shaft 31 and the roller 52 is driven through a sprocket chain 54 passing around a sprocket wheel 55 on the shaft 31 and a sprocket wheel 56 on the shaft 53.

45 In the operation of the portion of the in-

vention previously described, the sheet is fed between the rollers 10 and 16 and belts 8 and 9, and carried downwardly between the latter and discharged between the rollers 11 and 17, as particularly shown in Fig. 3. 50 The rocker arms 15 on being oscillated will act to deposit the sheet in successive folds; a suitable support being provided for the sheet adjacent to the lower end of the rocker arms.

55 In the present embodiment of my invention, I employ a horizontally disposed conveyer belt 57 on which the sheet articles are initially folded; the belt being maintained stationary during the folding operation and advanced to convey the folded article clear of the initial folding device, as will presently be described. The belt 57 is mounted upon supporting rollers 58 suitably mounted and arranged and passes around an end roller 59, as shown in Figs. 1 and 6, which roller is fitted with a sprocket wheel 60 around which passes a sprocket chain 61, which leads downwardly and around a sprocket wheel 62 on a shaft 63 extending 60 transversely beneath the conveyer belt 57.

65 The shaft 63 is fitted with a bevel pinion 64 meshing with a corresponding pinion 65 on a vertically disposed shaft 66 carrying a bevel pinion 67 at its upper end, which in turn meshes with a larger bevel gear 68 through which the belt 57 is intermittently driven. The gear 68 is mounted on a tubular shaft 69 journaled in a bearing 70 and loosely encircling a constantly driven shaft 71 on which a spur gear 72 is rigidly mounted. The spur gear 72 meshes with the spur gear 28 driven from the shaft 31 by the pinions 30. Splined on the shaft 71 is a sleeve 73 carrying a clutch member 74 adapted to be engaged with the end of the tubular shaft 69 and normally held out of engagement therewith by a spring 75 acting on a dependent arm 76 pivoted at 77 and connected to the sleeve 73.

70 Loosely mounted on the shaft 71 is a spur gear 78 meshing with a pinion 79 on the stud shaft 29 through which the spur gear 78 is constantly rotated when the shaft 31 is in operation. Formed on the outer face of the spur gear 78 is a cam or track 80 adapted to ride in and out of engagement with a roller 81 on the lower end of the arm 76; the cam being adapted to rock the arm 76 in opposition to the spring 75 to move the clutch member 74 into engagement with the tubular shaft 69, for the purpose of driving the conveyer belt intermittently to deliver the folded article to the refolding device 6.

75 The refolding device 6 embodies a pair of feed belts 82 and 83; the belt 82 being carried upon rollers 84 and 85 mounted upon dependent rocker arms 86 pivotally mounted axially of a shaft 87 supported on a suitable frame. The belt 83 passes around rollers 130

88 and 89 carried on the rocker arms '86; the roller 88 being carried on brackets 90 extending upwardly from the rocker arms, and the roller 89 being carried in slotted extensions 91 on the lower ends of the rocker arms. The belts 82 and 83 are arranged to yieldably contact each other at the point where they pass around the lower rollers 85 and 89, and for this purpose the roller 89 is mounted to have movement toward or away from the roller 85 and is normally held to position the belts 82 and 83 in contact with each other by means of springs 92, as particularly shown in Fig. 5.

15 Mounted on the shaft 87 is a sprocket wheel 93 engaged by a sprocket chain 94 passing around a sprocket wheel 95 on the shaft 59 from which the shaft 87 is rotated. A second sprocket wheel 96 is mounted on the shaft 87 engaged by a sprocket chain 97 passing around a sprocket wheel 98 on a shaft 99 carrying the roller 85, by which the latter and the belt 82 are driven. Mounted on the end of the shaft 99 opposite to the sprocket wheel 98, is a pinion 100 which meshes with an idler pinion 101 carried on a stud on the adjacent rocker arm and connected to a sprocket wheel 102 engaged by a sprocket chain 103 passing around a sprocket wheel 104 on a shaft 105 carrying the roller 88 and by which the latter is rotated. A second sprocket wheel 106 on the shaft 105 is engaged by a sprocket chain 107 passing around a sprocket wheel 108 on a shaft 109 on which the roller 89 is mounted and by which the latter is rotated. The chain and sprocket construction just described comprises a driving means whereby the belts 82 and 83 are driven with their adjacent portions moving in opposite directions.

40 Mounted on the shaft 87 is a roller 110 around which passes a conveyer belt 111 which may be a continuation of the belt 57 but is here shown as comprising a separate belt passing around a roller 112 positioned beneath the end conveyer roller 59 so that the article discharged from the conveyer belt 57 will be delivered to the belt 111 and carried upwardly over the roller 110 and fed between the belts 82 and 83.

45 The rocker arms 86 and the mechanism carried thereby are oscillated by means of connecting rods 113 attached to one end of the rocker arms and connected at its lower end to a wrist pin on the sprocket wheel 62.

50 In the operation of the invention, the article to be folded on being discharged from the mangle is delivered between the belts 8 and 9 and folded upon the conveyer belt 57, while the latter is stationary, by the oscillation of the rocker arm structure constituting the initial folding device *a*; the belt driving mechanism being so timed relative to the delivery of the article from the man-

5 gle and the initial folding mechanism that the belt will remain stationary during the folding period, and a sufficient lapse of time being provided to compensate for the varying lengths of the sheet articles to be folded. 70

75 The sheet article will thus be folded lengthwise on the conveyer belt, whereupon the latter will be set in operation by throwing in of the clutch 74, as before described, so as to advance the folded article in the direction of its length onto the upwardly extending conveyer belt 111 to deliver it onto the second folding mechanism *b*. The article is then fed downwardly between the belts 82 and 83 and discharged from the lower end 80 portion thereof between the rollers 85 and 89 onto a table 114 or other support; the oscillation of the second folding mechanism folds the previously folded article transversely, as indicated in Fig. 1, thereby completing the folding operations. 85

90 While I have shown and described a specific embodiment of my invention, it is obvious that various changes may be made in the details of construction and assemblage and arrangement of parts without departing from the spirit and scope of the invention as set forth in the appended claims.

I claim:

1. In a machine for folding sheet articles, 95 a dependent oscillatory structure, means whereby a sheet article may be advanced downwardly on said structure and delivered from the lower portion thereof, a conveyer belt for receiving the delivered sheet folded 100 longitudinally, and a second oscillatory structure arranged to receive the longitudinally folded sheet from said conveyer belt and folding said sheet transversely.

2. In a machine for folding sheet articles, 105 a conveyer belt, an oscillatory structure for receiving a sheet and delivering it folded longitudinally onto said belt conveyer, and a second oscillatory structure arranged at right angles to said first oscillatory structure to receive the longitudinally folded sheet and deliver said sheet folded transversely.

3. In a machine for folding sheet articles, 115 an oscillatory frame, a pair of upper rollers journaled on said frame, a pair of lower rollers journaled on said frame, an endless belt traveling over each upper roller and a complementary lower roller, said lower rollers being spaced close together and said upper rollers being spaced apart and the belts inclined relative to each other to receive the sheet articles, and means for oscillating said frame.

4. In a machine for folding sheet articles, 125 a dependent oscillatory structure, means whereby a sheet article may be advanced downwardly on said structure and delivered from the lower portion thereof, a conveyer belt for receiving the folded article, a sec- 130

- ond oscillatory structure arranged to receive the folded article from the said conveyer belt, and means for feeding the folded article through said last named oscillatory structure to refold same.
5. In a machine for folding sheet articles, an oscillatory folding device, a conveyer belt arranged to receive an article delivered from and folded by said device, means for driving said conveyer belt intermittently, and a second oscillatory folding device for refolding the articles delivered to said conveyer belt.
6. In a machine for folding sheet articles, 15 a dependent oscillatory structure, a pair of feed belts on said structure whereby a sheet article may be advanced downwardly on said structure and delivered from the lower portion thereof, means for driving said belts during movement of the oscillatory structure, a conveyer belt arranged to receive the article delivered from said oscillatory structure, and means for advancing said belt intermittently.
- 20 7. In a machine for folding sheet articles, an oscillatory frame, a pair of upper rollers journaled on said frame, a pair of lower rollers journaled on said frame, an endless belt traveling over each upper roller and a complementary lower roller, said lower rollers being spaced close together and said upper rollers being spaced apart to receive the sheet articles, one of said lower rollers being yieldingly mounted with relation to the other lower roller, and means for oscillating said frame.
8. In a machine for folding sheet articles, 40 an oscillatory frame, a pair of upper rollers journaled on said frame, a pair of lower rollers journaled on said frame, an endless belt traveling over each upper roller and a complementary lower roller, said lower rollers being spaced close together and said upper rollers being spaced apart and the belts inclined relative to each other to receive the sheet articles, means for feeding the sheet articles between said upper rollers, and means for oscillating said frame.
- 45 9. A machine for folding sheet articles comprising a pair of oscillating sheet feeding elements each of which is adapted to receive a sheet article at its upper end and to feed the article from its lower end and lay it in continuous folds, said elements being arranged at right angles to each other, and means for conveying the folded article from the lower end of one element to the upper end of the other element.
- 55 10. A machine for folding sheet articles comprising a pair of oscillating sheet feeding elements each of which is adapted to re-
- ceive a sheet article at its upper end and to feed the article from its lower end and lay it in continuous folds, said elements being arranged at right angles to each other, 65 a horizontal belt arranged beneath the discharge end of one element to receive the folded article, means for intermittently driving said belt to advance the folded article, and means for delivering the folded article from said belt to the upper end of the other of said folding elements.
11. In a machine for folding sheet articles, a horizontally extending endless belt, 75 means for intermittently driving said belt, means for laying a sheet article on said belt in continuous folds while the belt is stationary, and a second material folding means arranged at the end of the belt to receive the folded material from the belt.
12. In a machine for folding sheet articles, a horizontally extending endless belt, 80 means for intermittently driving said belt, means for laying a sheet article on said belt in continuous folds while the belt is stationary, and means for folding the article in continuous folds arranged at the end of said belt.
13. In a sheet article folding machine, a shaft, a roller on said shaft, a pair of dependent hangers pivoted on said shaft, a pair of parallel rollers carried on the lower ends of said hangers, an endless belt passing around the first named roller and one of the pair of rollers, a roller carried on the upper 95 portions of said hangers extending parallel to the first named roller and spaced therefrom, an endless belt passing around said last named roller and the other of the pair of rollers, and means for oscillating said 100 hangers.
14. In a sheet folding machine, a shaft, a pair of oscillating dependent hangers pivoted axially of said shaft, a pair of parallel rollers carried on the lower ends of said 105 hangers, a driven roller on said shaft, a belt passing around said driven roller and around one of the pair of rollers, an upper roller carried on said hangers paralleling the driven roller, and a belt passing around said upper roller and around the other of the pair of rollers, the inner leaf of said last named belt being inclined relative to the adjacent leaf of the other belt.
15. In a sheet folding machine, a pair of 115 endless belts arranged to have portions inclined relative to and facing each other between which a sheet to be folded may be passed, rollers supporting said belts, and means for oscillating said belts collectively.

MARGARET KELLEY.
